UNITED STATES PATENT OFFICE.

WILLIAM E. SOMERVILLE, OF COAL CITY, ILLINOIS.

FLYING-MACHINE.

1,189,302.

Specification of Letters Patent.

Patented July 4, 1916.

Application filed March 30, 1914. Serial No. 828,257.

To all whom it may concern:

Be it known that I, WILLIAM E. SOMERVILLE, a citizen of the United States, residing at Coal City, in the county of Grundy 5 and State of Illinois, have invented new and useful Improvements in Flying-Machines, of which the following is a full, clear, concise, and exact description, reference being had to the accompanying drawing, forming 10 a part of this specification.

My invention relates to improvements in flying machines and has for its object the production of a machine in which the angle of incidence of the main plane may be varied 15 at will while the machine is in the air.

A further object is the production of a machine with means for changing or varying the camber.

A further object is the production of a 20 machine having a stabilizer so designed as to keep the machine longitudinally stable.

A further object is the production of a machine of few parts and simple construction and one not liable to be easily broken 25 or damaged.

These and such other objects as may be attained by my machine are illustrated in the accompanying drawings in which—

Figure 1 represents a side elevation of my 30 machine with a part of the fuselage broken away exposing the mechanism; Fig. 2 represents an enlarged sectional view of a portion of Fig. 1 showing the stabilizer; Fig. 3 represents a top plan view of Fig. 1; Fig. 35 4 represents an enlarged sectional view of a portion of Fig. 1 showing the upper main plane and means for varying its angle of incidence. Fig. 5 represents a top plan view of Fig. 4 with a portion broken away.

Like numerals of reference indicate like 40 parts in the several figures of the drawings.

Referring now to the drawings, 6 represents the fuselage, 7 the chassis, 8 the engine and 9 the propeller of my machine; 10 represents the upper and 11 the lower main plane. At the center of the upper main plane is located an upwardly projecting fin 12.

Near the rear of the machine and at the 50 upper side is located the stabilizer comprising a forward portion 13 and a rear portion 13^a while below the stabilizer on the under side of the end of the fuselage is the rear support 14.

55 At the rear of the fuselage and arranged to swing horizontally on the upright rod 15

is the rudder 16. The required movement of the rudder is effected through the medium of two levers, one in the rear 17 on the rudder and one in the front 18 under the control of one of the operators, the two levers being connected by the cords 19, 19^a.

Seats 20—20^a are provided for two operators, positioned well in the front of the machine, all of the mechanism of the machine 65 except the engine being within the control of the operator on the rear seat 20.

The first important feature requiring description is the main planes 10 and 11 which comprise each a rigid rear portion 21 and 22, 70 and a movable front member 21^a, 22^a, the construction and operation of one of which are more clearly shown by reference to Figs. 4 and 5.

Secured to the front post 23 of the main 75 frame near the under surface of the top plane is a sprocket wheel 24 having on one face a bevel gear 25 in engagement with a corresponding bevel gear 26 on the end of a short upright journal shaft 27 which is in 80 turn provided at its upper end with a worm 28 engaging the teeth 29 of a segmental worm gear 30 movably mounted on the horizontal shaft 31 at the top of the frame. This shaft forms the front support for the rigid end 21 of the 85 upper plane and also a support for the movable end 21^a the frame 32 of which is rigid with the segmental worm gear 30, so when the segmental worm gear is rocked on the shaft 31 the angle of the member 21^a is varied 90 with respect to the plane 21 as indicated in dotted lines in Fig. 4. A similar mechanism in reverse position is provided for the lower plane as shown at 33 in Fig. 1.

The actual movement of the members 95 21^a—22^a is effected in the following manner: In a convenient position in front of the operator is located a sprocket wheel 34 with a suitable handle 35 over which wheel a chain 36 passes downwardly and over a second sprocket 37 mounted on a supplemental shaft 38. Sprocket chains 39—40 connect the upper and lower plane shifting mechanism with the chain 36 so the operator can by manipulating the lever 35 vary at 105 will the position of the front ends 21^a—22^a of the main planes.

Referring now to the stabilizer shown in detail in Fig. 2, each member 13 and 13^a comprises a frame over which is stretched 110 a canvas cover. The upper surface 41 is formed concave upward and the lower sur-

face 42 concave downward. This is effected by having the main crossbars 43 and 44 over which the covering material is stretched larger than the central bar 45.

5 The stabilizer 13 is mounted on the fuselage on supports 46—47, the front support 46 being arranged to permit a limited vertical movement. This movement is effected through the medium of a bell crank lever 10 47^a, the upper end of the upper arm of which is slidably mounted in a slot 48 in the supporting member 46 and the lower end of the lower arm is connected by a rod 49 to the operating lever 50.

15 The rear member 13^a of the stabilizer is rigidly mounted on the rocking shaft 51 and is rocked vertically by means of upwardly and downwardly projecting frames 52, 52^a whose ends have cord connections 53, 53^a 20 with the upper and lower ends of the operating lever 54.

It is thus apparent that by a proper manipulation of the levers 50—54 the front end of the member 13 and the rear end of the 25 member 13^a can be raised or lowered, thus making the stabilizer as a whole assume a greater or less degree of incidence either upwardly or downwardly as desired or to cause the two members to lie in substantially 30 the same horizontal plane as shown in the illustration in Figs. 1 and 2.

By reference to Fig. 3 it will be noted that the movable member 21^a of the upper plane does not extend the full width of the 35 plane but that the ends of the upper plane terminate in upturned end members 55, 55^a that are rigid with the main body of the plane. It is of course to be understood that this feature is not essential to this type of 40 machines but that the movable front member may, if desired, extend to the extreme end and the main plane terminate in the horizontal plane of the plane itself.

Referring now to the means for changing 45 the angle of incidence of the planes of the machine, this is best illustrated in Fig. 1. The upper and lower planes 10 and 11, in addition to being connected together by means of the posts 23, 23^a, are also pivotally 50 mounted on an immovable support or axis 56, the connection being made through the medium of rods 57, 57^a, 57^b and 57^c. A threaded connection shaft 58 is pivotally mounted at 59 to the lower plane and a worm 55 gear 59^a threaded on shaft 58 and held in place between the bearings 59^b is operated 60 through the medium of a hand wheel 60 and worm 61 enabling the operator by revolving the wheel to cause the connecting shaft 65 to travel forward or back, thus varying the angle of incidence of the planes in any desired manner, the chain 36 being tightened or slackened during this movement, but not so much as to interfere with its operation.

65 For instance, if the wheel is revolved so as

to cause the shaft to move backwardly, the point 59 is pulled upwardly and rearwardly, thus causing both planes to turn on the axis 56. The rear end 22, for instance, of the lower plane swings upwardly quite a distance 70 while the front portion 22^a would be depressed, though not in so great a degree owing to the position of the pivotal point 56.

Referring now to the advantage and the operation of my machine: It is a well understood fact that the same machine is not suited for speed and stability and capacity and that in the machines designed primarily for speed the other requisites are minimized and often ignored; so also a machine 75 designed for high climbing is not best adapted for long steady flights. By the adoption of the improvements present in my machine, however, all of these difficulties may be overcome and the machine 80 adjusted to give the best results regardless of the use for which it is required.

If swift climbing is desired depression of the front members 21^a—22^a and the front stabilizer 13, as well as the depression of 90 the member 13^a accomplishes the result. If one wishes to get off the ground or water quickly he will change to a higher angle of incidence and after he is in the air he can reduce the angle and the camber to get the 95 best possible speed out of the machine. It is a fact that in the design of the planes if the same is desired for speed, climbing is sacrificed, or vice versa, because of the relation of the camber to the chord. As an 100 illustration, the smaller the camber, the machine is efficient as a speed machine only and very inefficient as a climber, and the greater the camber the more efficient as a climber. Hence, in order to get an efficient 105 machine, something in addition to changing the angle of incidence of the machine must be done, so in order to get efficiency when the angle of incidence is changed I provide means for changing the depth of the camber; as the angle of incidence is increased 110 the camber can be increased, or vice versa. To accomplish the change in the depth of the camber various methods can be adopted. I change the camber by using the front 115 wing bar as a pivot; the section of the wing extending from the front wing bar to the leading edge is made to revolve around the said wing bar thereby changing the camber.

An improvement in the stabilizer or tail to secure the longitudinal stability of the flying machine automatically, is accomplished by making the stabilizer with camber on the top side as well as the bottom side. A two sided cambered stabilizer will give an equal reaction, i. e., if the aeroplane from some cause commenced a dive the camber on the upper side of the stabilizer would have the necessary pressure to force the tail 125 130

down and bring the aeroplane to a level keel. The same results would occur if the aeroplane started to climb, as the camber on the under side of the stabilizer would 5 right the aeroplane.

It is evident that I am not limited to the precise means illustrated in order to accomplish my objects as variations and modifications accomplishing the results are possible 10 without departing from the spirit of my invention.

I claim:

1. A flying machine comprising a longitudinally extending main frame, a plane 15 supporting frame pivotally mounted on said main frame and comprising members extending transversely with respect to said main frame, and lifting plane supported by said member, the front portions of said

plane being pivoted on said transversely extending member to move with respect to the rest of the plane.

2. A flying machine comprising a lifting plane and stabilizing means pivotally mounted back of the rear edge of said lifting planes and provided with upper and lower dished air engaging surfaces, and means for moving said stabilizing means bodily about its pivot and for holding said stabilizing device rigid with respect to said lifting plane in various positions.

In witness whereof, I have hereunto subscribed my name in the presence of two witnesses.

WILLIAM E. SOMERVILLE.
